UNITED STATES PATENT OFFICE.

GEORGE P. RASCK, OF DES MOINES, IOWA.

BAND-FASTENER.

SPECIFICATION forming part of Letters Patent No. 696,592, dated April 1, 1902.

Application filed June 10, 1901. Serial No. 63,947. (No model.)

To all whom it may concern:

Be it known that I, GEORGE P. RASCK, a citizen of the United States, residing at Des Moines, in the county of Polk and State of Iowa, have invented certain new and useful Improvements in Band-Fasteners, of which the following is a specification.

My invention relates to band-fasteners, and more particularly to that general class of fasteners which are especially adapted for use upon tanks and similar articles; and it has for its object to improve and simplify the construction of such devices; and to these ends it consists in a fastener embodying the features 15 of construction and arrangement of parts substantially as hereinafter more particularly set forth.

Referring to the accompanying drawings, Figure 1 is a plan view showing the fastener in position. Fig. 2 is a horizontal section on the line 2 2, Fig. 1; and Fig. 3 is a transverse section on the line 3 3, Fig. 1, looking in the direction of the arrow.

Heretofore numerous devices have been 25 made intended to accomplish the general objects of my invention, and, without pointing out specifically the constructions heretofore proposed I will state that experience shows that in a device of this character it is desirable 30 that the lugs shall be fastened to the band at or near the outer ends of the lugs, as otherwise upon screwing up or bringing the lugs together, as by means of a bolt, the bolt will force the outer ends of the lugs outward, and the inner adjacent ends will be 35 pressed into the tank or some of the staves of the tank, and it has been found difficult under these circumstances to tighten the bands satisfactorily. Furthermore, it is desirable 40 that the bolt or other fastening means connecting the lugs should be as near to the surface of the tank as possible, as in this way a more direct pull or strain upon the bands is secured. Furthermore, it is desirable that 45 the bands shall be held in the lugs by some quickly and easily adjusted devices which when in proper position will securely hold the ends of the bands in the lugs and which shall also permit the bolt to lie near the surface of 50 the tank. These and other features of improvement which will appear hereinafter are

met in the construction which I am about to describe.

Referring to the accompanying drawings, A represents a portion of a tank made up in 55 the present instance of wooden staves $a a' a''$, and B B' represent the ends of a band of metal or similar material passing around the tank, to which the lugs are attached and by means of which the band is tightened. Each 60 of the lugs is the complement of the other, and they can be used interchangeably, and therefore a description of one will apply to both. Thus there are shown two lugs C D, each preferably formed of metal, as phosphor-bronze or similar material, and each provided with what may be termed a "base" portion C', which is preferably curved slightly to conform to the curvature of the tank, although if the tank is of sufficient size this 70 curvature need not be appreciable. Rising from this base portion are upright sides C², and extending from these are the inclined top portions C³, and extending longitudinally through the center is a cylindrical or arched portion C⁴, having an opening C⁵ for the reception of a suitable bolt or rod E. This opening is cylindrical at its ends, and there is a cross-piece C⁶ beneath the opening, and which is arranged above the base portion C', 80 so as to form a longitudinal flat slot or passage C⁷ for the reception of the end of the band. The sides of the arched portion extend downward, as at C⁸, into the plane of this slot and form practically a runway on 85 each side between its ends and the upright sides C², and in these runways are arranged rollers F F'. A runway (shown in longitudinal section on the right-hand side of Fig. 2) is also formed by the inclined top C³ and a 90 wall C⁹, which is preferably beveled, as at C¹⁰, and the top C³ at the opening or inner end is provided with a toe or similar device C¹¹, which acts as a stop or retainer to hold the rollers F F' in position and keep them from 95 accidental displacement.

It will thus be seen that each lug has practically two runways for the rollers, and in between them is an arched portion for the reception of the bolt, and this is brought down 100 close to the base portion and is practically located between the runways, and the upper

portion of the opening C⁵ therein extends but slightly above the upper portion of the runways. In this way I get a very compact construction, using the least amount of metal, 5 and also accomplish other objects, which are before stated, such as bringing the bolt in close proximity to the band and staves.

I find that it is advantageous to use a roller on each side of the bolt or rod E for each end 10 of each band, as in this way I am enabled to bring the bolt into the position above described and also get a better bite or hold on the band, and especially so if perchance there is a little difference in the thickness of the 15 sides of the end of the band.

With this construction the operation of my device will be readily understood, and the end of the band, as B', is inserted in the slot C', and the roller F' is in the position shown 20 in dotted lines, which permits the ready insertion of the band. Then the roller F' is caused to assume the position approximately indicated in full lines in Fig. 2, and owing to the inclination of the top portion C⁸ it bites 25 or bears securely on top of the end of the band and presses it against the base portion C'. This can be done by gravity or by means of some proper instrument, which may be introduced into the opening between the parts 30 C⁸ and C¹⁰, and thus the lug is secured to the end of the band when both lugs are properly secured. The bolt E is passed through the openings C⁵ in the two lugs and can be tightened in any suitable way, as by the nuts E', 35 and it will be seen that the bearing portions of the nuts are near the ends of the lugs adjacent to the rollers F F', where they bite upon the ends of the band, so that there is almost a direct pull upon the band at this point, 40 avoiding the tendency to tilt above referred to. Moreover, the bolt being in the openings in the lugs which are located between the runways and nearly on a level therewith enables the bolt to be drawn close to the ends 45 of the bands, and this further aids in accomplishing the results desired.

With this construction the bands can be securely tightened and held in position and the lugs project the least possible distance beyond the circumference of the tank or other 50 device to which they are applied, and at the same time there is the least amount of metal in accordance with the strength of the lugs, it being so distributed as to produce great strength without undue weight. 55

What I claim is—

1. In a band-fastener, a lug having a slot for the reception of the end of the band, an opening for the reception of a bolt, runways one on either side of said opening, and a roller 60 mounted in each runway, substantially as described.

2. In a band-fastener, a lug having a slot for the reception of the end of the band, a centrally-arranged opening for the reception 65 of a bolt, runways one on each side of said opening, a toe controlling each runway, and a roller mounted in each runway, substantially as described.

3. In a band-fastener, a lug having a slot 70 for the reception of the end of the band, a longitudinal central opening for the reception of a bolt, inclined runways one on each side of said opening, and a roller mounted in each runway, substantially as described. 75

4. In a band-fastener, a lug having a longitudinal slot for the reception of the end of the band, a wall above the slot having an inclined face, an inclined top portion, the wall and top portion forming runways one on each 80 side of the central opening for the bolt, a roller mounted in each runway, and means for retaining the roller in position, substantially as described.

In testimony whereof I have signed my 85 name to this specification in the presence of two subscribing witnesses.

GEORGE P. RASCK.
